UNITED STATES PATENT OFFICE.

EDWARD STROUD, OF NEW YORK, N. Y.

PIANO-ACTION FRAME.

SPECIFICATION forming part of Letters Patent No. 363,488, dated May 24, 1887.

Application filed April 13, 1887. Serial No. 234,658. (No model.)

To all whom it may concern:

Be it known that I, EDWARD STROUD, of the city and county of New York, in the State of New York, have invented a new and useful Improvement in Pianos, of which the following is a specification.

My invention is applicable to upright pianofortes, and its object is to furnish a suitable support for the action-brackets, which will permit of the action being swung forward on the support as on a pivot, and also to hold the key-bottom in proper relation to the action and prevent its springing or warping, and at the same time to provide for the ready removal from the front of the instrument of the entire key-board, key-frame, and keys without disturbing in any way the position of the action. In order to provide for carrying upright pianos through narrow halls or other passages or spaces, the front portion of the case is frequently made removable from the remainder of the case, and to have such front portion of the case and the entire key-bottom and key-frame readily removable with the front of the case without disturbing the action is a great desideratum.

In carrying out my invention I provide, in connection with the action-brackets of an upright piano, a horizontal cylindric girt, which extends from side to side of the piano, and on which the brackets rest and may be swung forward as on a pivot. This cylindric girt may also serve as a rest for the back ends of the key-levers. I also provide the key bottom or plank with bearers or brackets at its rear edge, which are preferably of segmental form, so as to partly embrace the front of the cylindric girt and give the key bottom or plank such vertical support thereon as will prevent its springing or warping between its ends, and at the same time providing for the removal of the key-bottom with the keys forward without disturbing the girt or the action in any way. The end action-brackets have each a forwardly-projecting arm, and from this arm a brace or leg extends to the girt and prevents the bracket from turning on the girt, and this brace or leg is usually adjustable in length so that by its adjustment the bracket may be swung slightly inward or outward at its upper end. The brace or leg pref-

erably is not secured in the girt, but springs from a collar-section, which comprises a half-circular portion, the internal diameter of which corresponds with the diameter of exterior of the girt, and such collar-section is provided with a set-screw for securing it on the girt, as will be more fully hereinafter described.

In the accompanying drawings, Figure 1 is an elevation of such parts of a piano as are necessary to illustrate my invention, the plane of section being transverse to the horizontal girt and from front to back of the instrument. Fig. 2 is a front view of the parts shown in Fig. 1, 65 and showing two of the action-brackets, four being the usual number employed. Fig. 3 is a transverse section through the girt, representing the collar-section as fitting thereon and supporting the brace or leg of the action-bracket; and Fig. 4 is a plan of the parts shown in Fig. 3.

Similar letters of reference designate corresponding parts in all the figures.

A A' designate the upright-action brackets, 75 which are usually of cast metal. In an upright action there are usually employed two end brackets, A, and two intermediate brackets, A'. I have in Fig. 2 shown one end bracket and one intermediate bracket, and for 80 purposes of illustration they are, perhaps, nearer together than they would be in a piano.

B designates a horizontal girt, which extends from side to side of the piano, and in Fig. 2 one end wall to which the girt is secured is 85 represented by the line C. This horizontal girt is of cylindric form, and, to secure the necessary strength and stiffness with a light weight, it preferably consists of a tube or pipe. This tube or pipe may have flanges B' secured 90 upon its ends, and these flanges may be secured by screws b to the sides C of the case or frame. Each bracket A A' has secured to it rails D D', and has a segmental bearing, b', upon the girt B, and at its top is secured by a 95 screw, b'', or otherwise. It will therefore be understood that when desired the brackets A A', with the action, may be swung forward upon the girt B as on a pivot. For additionally supporting the brackets from the girt, I 100 construct the two end brackets A each with a forwardly-extending arm, b'', which is sup-

ported by a brace or leg, D^2 . As here represented, and as best shown in Fig. 3, the brace or leg D^2 does not spring directly from the girt B, but from the section of a collar, E, a portion of which is a semicircle of an internal diameter corresponding with the external diameter of the girt B. This collar is provided with a set-screw, e , and consequently when this set-screw is set up and a diametrically-
10 opposite portion of the collar-section is brought to a bearing upon the girt, as shown in Fig. 3, the collar-section is prevented from lateral displacement or disengagement with the girt, yet whenever the set-screw e is released the collar-
15 section can be laterally removed from and replaced on the girt B. The brace or leg, as here represented, has at the end a fork, d , and has a section, d' , which is screwed into this fork and into the collar-section E, and by turning
20 the section d' the brace may be lengthened or shortened to any extent desired. In the fork d of the brace is a cross-pin, d^2 , on which rests a V-shaped or concaved end of the projection b^3 of the bracket A.
25 F designates the key bottom or plank on which is supported the key-frame F^2 , and on this key-frame are fulcrumed at f the key-levers F^2 . As here represented, the rear ends of the key-levers F^2 are rabbeted at f' and
30 rest upon the horizontal girt B, a cushion, f^2 , of felt or other soft material, being interposed. The key bottom or plank F has secured upon it brackets f^3 , which have segmental bearing portions f^4 resting against the front of the girt
35 B. These segmental bearing portions f^4 embrace enough of the circumference of the girt B to steady and support the key-bottom against vertically moving by warping or springing, and at the same time they permit the key-bot-
40 tom to be readily removed from the front of the instrument without manipulating any devices to disengage it from the girt B. As best represented in Fig. 4, the collar-section E has a lateral projection, e' , in which the brace or
45 leg D^2 is inserted, and which serves to bring such brace or leg directly beneath the projection b^3 on the bracket A.

If it be desired to remove the front of the case in order to pass the piano through contracted passages or spaces, the key-bottom, to-

gether with the key-frame and key-levers, may be entirely removed from the front of the instrument; and my construction also provides for swinging the action forward upon the horizontal girt B as on a pivot when access is desired to it for any purpose. As here represented, the key-levers F^2 act through suitable stickers or rods, h , upon the levers h' , and through them serve to actuate the corresponding parts of the action.

55

60

What I claim as my invention, and desire to secure by Letters Patent, is—

1. The combination, with the action-brackets of an upright piano, of a horizontal cylindric girt extending from side to side of the 65 piano, and on which the brackets rest and may be swung forward as on a pivot, substantially as herein described.

2. The combination, with the action-brackets and key-levers of any upright piano, of a 70 horizontal cylindric girt extending from side to side of the piano, on which the brackets are supported, and which serves as a rest for the back ends of the key-levers, substantially as herein described.

75

3. The combination, with the action-brackets of an upright piano and the key bottom or plank, of a horizontal cylindric girt on which the brackets are supported, and bearers or brackets on the key-bottom fitting against but 80 otherwise having no connection with said girt, substantially as herein described.

4. The combination, with the end bracket, A, having a forwardly-projecting arm, of the girt B and a brace or leg, D^2 , for supporting 85 the bracket through its arm and preventing the bracket from turning on the girt, and which is adjustable in length, substantially as herein described.

85

5. The combination, with the end bracket, 90 A, having a forwardly-projecting arm, b^3 , of the girt B, the collar-section E, provided with a set-screw for securing it on the girt, and the adjustable brace or leg extending from the collar-section and supporting the bracket through 95 its said arm, substantially as herein described.

EDWARD STROUD.
